BOTTLE TOP COVERING

Andrew C. Klein and Walter E. Payne,
Reading, Pa.

Application August 15, 1938, Serial No. 225,072

5 Claims. (Cl. 226—86)

Our invention relates to methods of, and means for, folding flexible sheets over the ends and along the sides of bottle necks and the like, and particularly to such methods and means as employed in forming sheet hoods or wrappers of "Cellophane" for the tops of bottles containing milk or other liquids.

It has heretofore been suggested, particularly among the sanitary precautions in the distribution of beverages, such as milk and other liquids, to place hoods or caps extending over the tops, and along the sides, of the bottles, these caps being constructed of flexible sheet material, such as "Cellophane".

In forming and mounting a hood of the above-indicated type, it has been usual to draw the sheet material from a roll to position in a horizontal plane over the bottle, cut the sheet to square form, part of which remains in such plane across the top end of the neck, and the remainder of which is pressed downwardly along the neck sides, where it is bound as by paper tape.

A prior means for pressing the side portions of the hood or sheet downwardly along the bottle neck sides, comprises a flexible rubber layer having a circular opening therethrough of smaller diameter than the neck top, and radial slits extending outwardly in the layer from the inner periphery of the opening, whereby to form radial fingers or arms. When the neck is pressed against the "Cellophane" sheet and through the opening in the rubber layer, the above-mentioned radial rubber fingers yield axially of the neck, and descend along the sides of the neck with a wiping action and the fingers pointing upwardly, to press the "Cellophane" around, and downwardly along the sides of, the neck for the reception of the retaining tape.

Consequently, when the rubber layer and the bottle are withdrawn from each other, there is a complete reversal of axial flexure of the rubber fingers, during the initial motion of which, with the fingers pointing upwardly and the friction of the rubber, there is a tendency to undo the downward sheet-forming motion effect, until the fingers are turned to position pointing downwardly.

This action is adverse to the hood, and with repetition, very quickly breaks off the fingers, whereby frequent renewals of the rubber layer are necessary.

The expense incident to this feature has caused operators to ignore the breaking of fingers to a point where hoods further deficient from this

cause have been produced, and has been a reason against the installation of the entire machine.

Also, with such prior device, the "Cellophane" is folded or affected entirely by the rubber layer, which is held in place at its peripheral outer extremities by a rigid support, which of itself does not operatively engage or act on the hood.

Further, in the operation of the above-mentioned prior device, a plunger is required for ejecting the bottle top from the rubber layer, this plunger being power operated through cam means, and requiring accurate timing and considerable expensive mechanism of substantial size and large number of parts.

It is among the objects of this invention to avoid the disadvantages of a prior device of the above-indicated general type, and to improve the method of, and means for, installing the wrapper.

Another object of our invention is to provide a device of the above-indicated character that is free from flexure of parts axially of the bottle neck, and from fatigue or damage resulting from such flexure.

Another object of the invention is to render the device more durable, to avoid frequent renewal of parts, and to reduce the number of the latter.

Another object of the invention is to reduce the amount of flexible sheet material, or "Cellophane," necessary to produce an effective wrapper.

Another object of the invention is to prevent withdrawal or rumpling effect on the wrapper after installing it.

Another object of the invention is to render the wrapper more effective and neater in appearance, and to more efficiently install it, irrespective of the size of the bottle.

Another object of the invention is to provide a rolling, or more effective, action more on the order of ironing the wrapper in place along the sides of the bottle neck.

Another object of the invention is to provide a device of the above-indicated character in which a part thereof is better adapted as a permanent part of the machine.

Another object of the invention is to assist the withdrawal of the bottle necks from the wrapper installing means, by movable means in which energy is stored by action against the bottles during the bottle installing movement, and in which accuracy of fit against the bottle tops is ensured irrespective of minor discrepancies in the levels of such tops.

Another object of the invention is to provide

55

a plunger device, for assisting in the withdrawal of a bottle from position after being capped, that has a pressure effect tending to fit the cap in position, and that is prevented from disturbing the sheet or being held thereto from vacuum effect caused by the pressure.

Another object of the invention is to provide auxiliary means assisting in rendering the top layer of a flexible bottle cover free from wrinkles 10 whereby to add to the effectiveness of the cover and, where such cover is transparent, to provide clear vision therethrough.

Another object of the invention is to provide a device of the above-indicated character that is 15 simple and durable in construction, economical to manufacture, and effective in its operation.

With such objects in view, as well as other advantages which may be incident to a utilization of the improvement, the invention comprises the elements and combinations thereof hereinafter set forth and claimed, with the understanding that the several necessary elements constituting the same may be varied in proportion, arrangement and texture, without departing from the spirit and scope of the invention as intended, and as set forth in the drawings, specification and claims.

In order to render the invention more clearly understood, means are shown in the accompanying drawings for carrying the same into practical effect, without limiting the improvements in the useful applications thereof to the particular constructions shown and described, which are given merely by way of example.

35 In the drawings:

Figure 1 is a view taken substantially along the line 1—1 of Fig. 2 of a device for effecting certain actions in folding a flexible sheet over the end and along the sides of a bottle neck and the like, 40 in accordance with the invention;

Fig. 2 is a top plan view of the device of Fig. 1;

Fig. 3 is a view partially in side elevation and partially in longitudinal section of a plunger device for cooperation with the device of Figs. 1 45 and 2;

Fig. 4 is a view, similar to Fig. 2, of a modified form of the device thereof; and

Figs. 5, 6, 7, and 8 are progressive sequence 50 diagrams of portions of the devices of Figs. 1, 2 and 3 in cooperative relation to each other in the operation of covering or capping the neck or top of a milk bottle.

Referring to Figs. 1 and 2, the device is in the 55 form of a rectangular support or plate A constructed of metal, or other material, including upper and lower plates 9 and 10, respectively, separately joined to each other, as by screws 11, and having a central opening 14 through both 60 plates.

The upper plate 9 has a circular top riser 15 for fitting it to a part of a machine in which the device is adapted to operate. Holes 12 are adapted to receive screws for attaching the device to 65 the machine.

Each plate 9 and 10 has a circular recess in its broad side facing the other plate to form an annular channel 16 for the reception of substantially garter spring means 17, which is maintained 70 in movable relation to the support by annular inner peripheral overhanging portions 20 and 21 on the plates 9 and 10, respectively.

The spring, in this instance, is a helical spring constructed from an initially straight helix having inturned ends 22 (Fig. 1), and a few of the

turns at each end 23 (Fig. 2) interlocked with turns at the other end, as by placing them together with a screw action; the inturned ends 22 being provided to avoid tearing a flexible sheet 25 (Figs. 5-8). The diameter of the overhang 5 26, in this instance, is slightly smaller than the diameter of the overhang 21 caused by space limitations, and to take advantage of the available space to ensure proper limitation of radially inward contraction of the spring 17.

10 As shown, the spring retaining means, including the overhanging portions 20 and 21, and other parts of the support, function, in effect, by partially embracing the spring from positions radially outwardly thereof to positions radially 15 inwardly of the axis of the helix, but radially outwardly from the inner periphery of the spring or garter. As shown, the spring 17 is free to expand radially outwardly in the channel 16, but is limited in its inward contraction by the overhangs 26 and 21, which are of larger diameter than the inner diameter of the spring, whereby the latter freely engages and acts radially against the neck of a bottle, as will hereinafter more 20 clearly appear.

25 In the device thus far described, the overhang 21 and the spring 17 constitute means having axially successive sheet-affecting actions on the sheet 25, as will also later appear.

30 Referring to Fig. 3, a plunger device B there- 35 in shown, comprises a bracket or bearing 27, constituting a part of the above-mentioned machine, for the support of a plunger rod 30 having a vertical slot 29 for cooperation with a pin 31 in the bracket 27 to permit vertical reciprocation, but to prevent turning, of the rod in the bracket or other bearing means. A nut or cap 32, held at the top of the rod 30, as by a pin 35, limits downward motion of the rod.

35 A compression spring 36 embraces the rod 30 40 between the bracket 27 and an element 37 that is longitudinally slidably mounted on the rod and adapted to be held in fixed adjusted position, as by a screw 40.

45 A washer-like element 41 is loosely or yieldably mounted at the lower end of the plunger rod 30, as by being mounted on a reduced section 42 of the rod of slightly greater length than the thickness of the element 41 at this point, and held in place, as by a nut 45.

50 The element 41 may be merely loosely mounted, as shown, or this looseness may be damped by a yieldable or spring washer, or other means between the rod and the element. This feature provides accurate seating of the element on the 55 bottle top, irrespective of minor discrepancies in the level or contour of the latter.

A rubber washer 46, or equivalent means, may be angularly or otherwise disposed on the element 41 such that, when the element is pressed against the top of the bottle neck, it will provide a radial stretching effect on "Cellophane" or other flexible sheet material across the top of the bottle or neck by tending to press the sheet downwardly and outwardly at the top perimeter of the neck. 65 This feature assists in fitting the sheet to the bottle and rendering the top layer thereof smooth, and provides clearer vision through the layer.

To ensure against the formation of a vacuum or suction between the element 41 and the flexible sheet or wrapper at the top of the bottle, a vent hole 47 is provided through the washer 46 and the element 41. This feature is provided, since the plunger is adapted to urge and release the bottle downwardly, and not to pick it up, or to 75

disturb the wrapper after it has been formed.

In the form of the device of Fig. 4, the structure is substantially the same as that of Figs. 1 and 2, except for the shape of an opening 14a corresponding to the opening 14. The opening 14a is substantially rectangular, but may be oval or of other shape to adapt the device to bottle necks or the like of other cross sectional contours.

10 Parts of the device of Fig. 4 corresponding to parts of the device of Figs. 1 and 2, are designated by corresponding reference characters having the subscript (a).

15 Referring to Figs. 5-8, illustrating the operation of the devices of Figs. 1-3, above set forth, in placing the sheet 25 on a bottle 50, Fig. 5 illustrates an initial or first position, in which the devices A and B are spaced above the bottle, and the sheet 25 is between the device A and the 20 bottle.

25 As the bottle is raised, or the devices A and B lowered, an upper flange 51 of a neck 52 of the bottle 50 may first engage the overhang 21 of the lower plate 10 in a relation somewhat as 30 diagrammatically illustrated in Fig. 6; the initial bending of the sheet 25 thus being effected by the overhang which is made up of elements of its periphery having fixed radial position on the support formed by the plates 9 and 10 around the aperture 14, and being shaped, as shown, to render its bending or folding effect gradual, and not of sudden character tending to damage the sheet, as might be effected by a sharp edge of small diameter compared to the flange 51.

35 As the operation continues to the phase of Fig. 7, the spring 17, being of smaller diameter than the flange 51, and protruding radially inwardly from the channel 16, engages and rolls over this flange about the circular axis of the helix, thus 40 constituting substantially anti-friction or anti-wiping means for continuing the formation of the hood from the sheet 25 without flexure of any of the parts, or fatigue from such flexure, axially of the bottle neck.

45 Upon continued operation, as illustrated in Fig. 8, the bottle top engages the washer 46 of the plunger B, whereby to accurately seat the element 41, as above set forth, and to provide the aforesaid radial stretching effect on the sheet 25 across the top of the neck 52. This action also 50 axially compresses the spring 36 to provide sufficient reactive axial force to ensure quick withdrawal of the bottle, irrespective of the size of the latter.

55 With the sheet 25 formed into a smooth fitting hood, wrapper or cap over the top and along the sides of a bottle neck or the like, as above set forth, a tape or band 55 (Fig. 8) may be applied around the neck 52 below the flange 51, as an element, and by means, not of themselves constituting parts of this invention, but in cooperation with, or including, which the invention is comprised.

60 The invention may, of course, be variously operated, such as without the spring 17 in certain instances where the lower overhang 21 may be sufficient, or with solid bodies, such as exhibition bottle shapes, or with like articles having little or no flange, such as tubes, rods and other like articles of various cross sectional contours; main 65 considerations being the permanency of the parts, as distinguished from readily destructible material, such as the rubber fingers above set forth, the reduction in number of parts, effective operation, economy of construction, a better product,

the enhancement of the machine, and various other considerations making the invention an improvement generally in its field.

We claim as our invention:

1. In a device for forming a flexible sheet hood on a milk bottle and the like having a neck flange, a body having a vertical opening entirely therethrough for receiving the bottle neck by relative movement of the bottle and the body from a position of the bottle top under the sheet below the body to a position of the neck through said opening with a portion of the sheet over the top and along the neck to provide for binding the sheet around the neck above said body below said flange, means on said body including spring-biased sheet-engaging elements for exerting yieldable garter-like pressure against the sheet around the neck, and means providing for bodily movement of said sheet-engaging elements relative to said body and centering the same horizontally relative to the vertical axis of said opening.

2. In a bottle-hooding device, a body structure having an opening therethrough and a chamber portion around said opening, radially-inner spring centering means on said body forming a slot-like aperture around said opening, and garter-like spring means in said chamber around said opening normally radially contracted to position engaging said spring centering means centered thereby relative to, and projecting into, said opening through said slot and radially expandable in the chamber away from said centering means.

3. In a bottle-hooding device, a body structure having a vertical opening therethrough and a horizontal chamber portion around said opening, radially-inner spring centering means on upper and lower portions of said body, the said spring centering means on at least one of said body portions overhanging the chamber and with the spring centering means on the other body portion forming a horizontal slot around said opening of less vertical width than the chamber, and garter-like spring means positioned in said chamber around said opening of greater vertical width than said slot normally radially contracted to position engaging said spring centering means centered thereby relative to, and protruding into, said opening through said slot and radially expandable in the chamber away from said spring centering means.

4. In a bottle-hooding device, a body having a vertical opening therethrough and a horizontal chambered portion around said opening including radially-inner spring-centering portions overhanging the chamber upwardly and downwardly from lower and upper portions, respectively, of the body forming a horizontal slot around said opening of less vertical width than the chamber, and a garter spring positioned in said chamber around said opening of greater vertical width than said slot normally radially contracted to position engaging said overhanging portions centered thereby relative to, and protruding into, said opening through said slot and radially expandable in the chamber away from said overhanging portions.

5. In a bottle-hooding device, a body having a vertical opening therethrough and a horizontal chambered portion around said opening having an inner surface of substantially C-section including radially-inner spring-centering curved inner-surface portions overhanging the chamber upwardly and downwardly from separate lower and upper portions, respectively, of the body forming a horizontal slot around said opening of

less vertical width than the chamber, a garter spring of rounded section positioned in said chamber around said opening of greater vertical width than said slot normally radially contracted to position substantially tangentially engaging the curved inner surfaces of said overhanging portions centered thereby relative to, and protruding into, said opening through said slot and

radially expandible in the chamber from said overhanging portions, said separate portions providing for the reception of said garter spring to the chamber independently of said slot, and means for connecting said separate portions to each other radially outwardly of said spring.

ANDREW C. KLEIN.
